UNITED STATES PATENT OFFICE.

JOHN F. HAY, OF ERIE, PENNSYLVANIA, ASSIGNOR TO ERIE MALLEABLE IRON COMPANY, OF ERIE, PENNSYLVANIA, A CORPORATION.

APPARATUS FOR FORMING CORES.

No. 799,847.

Specification of Letters Patent.

Patented Sept. 19, 1905.

Application filed October 17, 1904. Serial No. 228,895.

To all whom it may concern:

Be it known that I, JOHN F. HAY, a citizen of the United States, residing at Erie, in the county of Erie and State of Pennsylvania, have 5 invented new and useful Improvements in Apparatuses for Forming Cores, of which the following is a specification.

This invention relates to apparatuses for forming cores; and it consists in certain improvements in construction thereof, as will be 10 hereinafter fully described, and pointed out in the claims.

The purpose of the invention is to provide an apparatus by which a core may be readily 15 formed, having chills so arranged in the core as to prevent the formation of defects in the castings for which the cores are used.

Great difficulty has heretofore been encountered in casting cored articles having angles, 20 especially where the casting is of iron from which malleable iron is formed. This is particularly true in that class of castings known as "pipe-fittings," such as T's and elbows. With such castings difficulty has been encountered 25 at the angle where defects are apt to occur, producing weakness and in many cases forming minute openings through the walls of the fittings, so as to render them practically useless.

30 Among the objects of the invention is to form a core apparatus by which a core may be so provided with chills as to obviate these difficulties.

The invention is illustrated in the accompanying drawings, as follows: Figure 1 shows 35 a plan view of one half of the core-box with the apparatus in place therein ready to be inserted in the material in the box; Fig. 2, a plan view of the other half of the core-box 40 with the chill and follower in the position assumed after the chill has been forced to position; Fig. 3, a plan view of a finished core; Fig. 4, a section on the line 4-4.

The apparatus shown is designed to form 45 the core for a T and comprises the core-box A, having the main passage a and cross-passage a' . The parts of the core-box are brought into register by the usual dowels a^3 entering the perforations a^4 . The angles have the filling A'. Openings a^2 are extended through this filled-in portion to the apex of the angle.

A chill B, preferably pointed, is dropped into the openings a^2 and forced into the material forming the core by a follower C. In the 50 ordinary formation of the core the core ma-

terial will be placed in the box in the usual manner. The chill B is then forced into the core by the use of the follower C. The material forming the core need not be completely rammed prior to the insertion of the chill. 60 A stop c is preferably provided so that the end of the follower will bring the surface of the chill just flush with the surface of the core.

By making the opening a^2 of greater length than the chill the chill may be dropped into 65 it and the follower readily brought into place in the opening, the opening forming a guide for the chill and follower, through which the chill may be inserted through the action of the follower. 70

What I claim as new is—

1. In an apparatus for forming cores, a core-box having an opening through the walls thereof at a point corresponding to the point of stress in the resulting casting for the insertion 75 of chills.

2. In an apparatus for forming cores, a core-box for forming articles having an angle, said box having an opening through its walls at the angle for the insertion of the chill. 80

3. In an apparatus for forming cores, a core-box having an opening through the walls thereof at a point corresponding to the point of stress in the resulting casting for the insertion of a chill, said opening having greater length 85 than cross dimension.

4. In an apparatus for forming cores, the combination of the core-box having an opening through the walls of the box at a point corresponding to the point of stress in the resulting casting; and a follower adapted to 90 pass into said opening to force a chill into the material in the box.

5. In an apparatus for forming cores, the combination of the core-box having an opening through the walls of the box at a point corresponding to the point of stress in the resulting casting; and a follower adapted to pass into 95 said opening to force a chill into the material in the box, said follower being provided with a stop to limit its inward movement to bring its end flush with the inner surface of the box. 100

In testimony whereof I have hereunto set my hand in the presence of two subscribing witnesses.

JOHN F. HAY.
